MAGNETIC TAPE CARTRIDGE

Raymond B. Larsen, Riverview Road,
Riverton, Wyo. 82501

Continuation of abandoned design application Ser. No.
26,195, Nov. 27, 1970. This application May 25, 1972,
Ser. No. 257,068

Term of patent 14 years

Int. Cl. D14—99

U.S. Cl. D26—14 B

FIG. 1 is a perspective view of a magnetic tape cartridge illustrating my design;

FIG. 2 is a top plan view thereof;

FIG. 3 is a bottom plan view thereof;

FIG. 4 is an end view;

FIG. 5 is a side elevational view;

FIG. 6 is a front elevational view; and

FIG. 7 is a side elevational view.

This is a continuation of design application Ser. No. 26,195, filed Nov. 27, 1970 and now abandoned.

I claim:

The ornamental design for a magnetic tape cartridge, as shown.
